UNITED STATES PATENT OFFICE.

NELSON SMITH, OF VANCOUVER, CANADA.

VOTING-MACHINE.

SPECIFICATION forming part of Letters Patent No. 763,436, dated June 28, 1904.

Application filed May 15, 1903. Serial No. 157,260. (No model.)

To all whom it may concern:

Be it known that I, NELSON SMITH, a citizen of the United States of America, residing at the city of Vancouver, in the Province of 5 British Columbia, Canada, have invented a new and useful Improvement in Voting-Machines, of which the following is a specification.

My invention relates to an improved voting-machine designed to automatically record and enumerate votes for one or more candidates, while at the same time the register is entirely secret, though under the control of the officer in charge of the polling-booth to see that only 15 one vote is recorded.

The construction and operation of my invention are fully described in the following specification and illustrated in the drawings which accompany it.

20 Figure 1 is a cross-section through one of the vote-registers; Fig. 2, a longitudinal section through a series of them; Fig. 3, a detail showing the electric contact by which the recording of each vote is announced. Fig. 4 is 25 a view which illustrates a modified arrangement of parts of my invention, whereby a vote may be recorded for any candidate who has not been previously nominated. Fig. 5 is a perspective view of the interior of a voting-apartment furnished with my devices. Fig. 30 6 is a cross-section taken practically on the lines 6 6 of Fig. 1. Fig. 7 is a detail perspective view of the rod 24 and its connection with the member 23.

35 Each vote-register consists of a ribbon or strip 2 of paper or similar material adapted to receive the impress of a self-inking stamp. This ribbon is coiled on a freely-rotatable reel 3 under the top 4 of a table or inclosed frame, 40 on which the apparatus is secured in each divided apartment of the polling-booth, and one end of the ribbon is brought through a slot or opening 5 in the top 4 and passing over a short smooth stamping-surface 4^a is taken 45 down through a similar opening 6 and coiled on one of a series of reels 7, secured to a shaft or spindle 8, suitably supported in bearings and rotatable by means of a handle 9 on the outer side of the apartment.

50 The movement of the paper strip 2 off each

reel 3 is checked by a spring 10, which imposes a light frictional resistance between the spring and the surface of the aperture 5, and the movement of the spindle 8 of the reels 7 is checked against backward rotation by a 55 pawl 11, engaging a ratchet-wheel 12, secured to the spindle within the casing.

Over each stamping-surface 4^a is mounted a hand-stamp 13, which in the practical arrangement of my invention is preferably an automatically-actuated progressively-numbering and self-inking stamp of any well-known make, and the shaft of the said stamp 13 is extended at the ends to form guide keys or projections 15 and 16. The projection 15 is 65 designed to actuate an electric contact between the terminals 17 and 18 of an electric circuit in which is an alarm-bell 20 and an annunciator 21 outside of the voting-apartment when the hand-stamp is depressed, whereby to indicate both to the ear and eye that a vote has been recorded. The other produced guide 70 16 engages a pivotally-mounted detent or latch 22, which springs over 16 and retains the stamp in its lower position until released by 75 means of a slidable rod 24, which is in engagement with the lower ends 23 of the pivotally-mounted detents 22 and is operated by a handle 25 outside of the voting-apartment.

A spring 26 tends to keep the detent-levers 80 in the normal position of engagement and permits the detent to spring over the end 16 when the stamp is depressed.

The mechanism of the stamps is inclosed by a suitable cover 27, through the top of which 85 the plunger-handles only are allowed to project.

In use a numbering-stamp and registering-ribbon are furnished for each nominated candidate, whose name is clearly indicated on each stamp either on the cover adjacent to each handle or, preferably, in the end of the handle itself, and the voter, having satisfied the officer of his qualification, enters the apartment and presses down the handle bearing the name of the candidate in whose favor he desires to record his vote, which operation thus impresses the desired number upon the ribbon and actuates the bell and the annunciator to indicate that the vote has been recorded, 100

the stamp being retained by the detent 22 in the downward position until released by the pulling out of the handle 25 from the outside by the officer in charge, who also, by turning the handle 9, advances the paper ribbons for the next impression without having any means of ascertaining on which ribbon the vote was cast.

Where it is permissible for votes to be given to persons who have not been previously nominated as candidates, one of the ribbons, as shown in Figs. 4 and 5, is not furnished with a numbering-stamp; but the paper strip where it passes over the surface 4^a on the upper side of the table is protected by a cover-plate 28, having an aperture which will permit of the name of a candidate being written on the paper strip.

Having now particularly described my invention and the manner of its operation, what I claim as new, and desire to be protected in by Letters Patent, is—

1. In a voting-machine of the character described; the combination of a suitable frame and a table-top connected therewith having a pair of opposing slots; a stamping mechanism mounted on the table between the said slots, the said mechanism including a vertically-movable impression-roller, and a record-receiving mechanism which comprises a reel, an impression-receiving band coiled thereon and which passes through the table-slots and under the impression-roller, a take-up reel for the said bands, a trip device for holding the impression-roller in its depressed position, and

an annunciator and means for actuating the said annunciator controlled by the depression of the said impression-roller.

2. In a voting-machine as described, the combination with the frame and a table which forms a part thereof, said table having a pair of parallel slots inclined in opposite directions and an annunciator; of a stamping mechanism mounted on the table-top between the slots therein, said mechanism consisting of a vertically-movable hand-stamp having lateral projections 15 and 16, and an impression-band that passes under the said stamping mechanism and through the opposite slots in the table, a roller upon which one end of the band is coiled, a second or take-up roller for the said band, the said roller being mounted under the table, a pivoted dog or trip adapted to automatically interlock with the projections 16 of the stamp when it is depressed whereby to hold the said stamp in such depressed position and means for actuating the annunciator adapted to be engaged by the projection 16 of the stamp-roller, and a means for shifting the dog or trip to release the said stamp-roller, all being substantially shown and for the purposes described.

In testimony whereof I have signed my name to this specification in the presence of two subscribing witnesses.

NELSON SMITH.

In presence of—

ROWLAND BRITTAINE,
ELLIEE WEBBER.
